UNITED STATES PATENT OFFICE.

CLARENCE W. N. PALMER, OF GREENCASTLE, PENNSYLVANIA.

ELECTRIC RAT-TRAP.

1,112,228.

Specification of Letters Patent. Patented Sept. 29, 1914.

Application filed November 21, 1912. Serial No. 732,714.

To all whom it may concern:

Be it known that I, CLARENCE W. N. PALMER, a citizen of the United States, and a resident of Greencastle, in the county of 5 Franklin and State of Pennsylvania, have made certain new and useful Improvements in Electric Rat-Traps, of which the following is a specification.

My invention relates to improvements in 10 rat traps, and it consists in the combinations, constructions, and arrangements herein described and claimed.

An object of my invention is to provide a 15 rat trap in which the rodent is killed by an electric shock, and his body deposited in a proper receptacle.

A further object of my invention is to 20 provide means whereby the trap when once operated will automatically reset itself, thus doing away with the necessity of setting the trap each time it is used.

Other objects and advantages will appear 25 in the following specification and the novel features of the invention will be particularly pointed out in the appended claims.

My invention is illustrated in the accompanying drawings forming part of this application in which—

Figure 1 is a vertical sectional view 30 through the device on the line 1—1 of Fig. 2, Fig. 2 is a section on the line 2—2 of Fig. 1, Fig. 3 is a section on the line 3—3 of Fig. 1, Fig. 4 is a section on the line 4—4 of Fig. 3, and Fig. 5 is an enlarged section along the 35 line 5—5 of Fig. 2.

In carrying out my invention I provide 40 a receptacle 1 which forms the base portion of the device. Mounted upon the base portion are uprights 2, which bear at their tops a stationary shaft 3. Secured to the shaft is 45 an insulating ring or collar 5, while on each side of the collar are loosely mounted hubs 6. Set into the hubs are a series of radially extending plates 7, which form supports for the plates 9 that go to make up the radiating arms or platforms. In Fig. 5 I have shown 50 these plates as being secured to the members 7 by means of bolts 10, suitable insulating strips 11 being interposed between the mem-

bers 9 and the radiating supports 7, the bolts 50 also being insulated by means of bushings 12. Between the outer ends of the plates 9 are spacing blocks 13. In Fig. 1 I have shown four of these arms or platforms at A, B, C and D respectively. 55

Mounted upon brackets 14 on each arm is a plate 15 which is normally inclined downwardly as shown in Fig. 1, and which has a pivotal connection with a rod 16 disposed between the plates 9 of each arm. The lower 60 ends of the rods 16 are pointed and are arranged to enter a recess in the top of the collar 5. The rod 16 is of sufficient weight to enter this recess without the use of a spring. Each arm is provided with a pin or 65 hook for the bait 17.

The device is provided with an external casing 18 which rests on the top of the receptacle 1. This casing is cut away at its front upper half as shown at 19 in Fig. 1 70 to provide an opening for the entrance of the rodent. An inclined run-way or ladder 20 leads to a platform 21, which is arranged to register with the arms when the latter are stationary. 75

In order to provide for killing the rat by 80 an electric shock I loosely mount a pair of insulating wheels 21 and 22 on the shaft 3. Each of these wheels is provided with a conducting ring such as that shown at 21^x and 22^x. The ring 21^x is connected by means of the wires 23 to the arms A and C, while the ring 22^x is connected by means of the wires 24 to the arms B and D, these wires 85 passing through the insulating wheel 21, as shown in Fig. 2. A brush 25 bears on the ring 21^x while a similar brush 26 bears on the ring 22^x. One of these brushes is connected by means of a wire such as that 90 shown at 27 with the positive source of current and the other brush is designed to be connected to the negative source of current. This source of current may be any source 95 which is suitable for the purpose intended. The rings 21 and 22 are secured to the adjacent hub member 6 so as to rotate therewith in any suitable manner, as by means of pins or arms 6^a (see Fig. 2).

From the foregoing description of the various parts of the device the operation thereof may be readily understood.

The rat or other rodent scenting the bait 5 ascends the ladder 20 and passes from the platform 21 on to one of the arms, such as that shown at B in Fig. 1. He rises to get the bait 17 and places his front feet on the plate 15. The impact causes the lifting of 10 the rod 16 from the slot in the top of the collar 5. The weight of the animal causes the platform or arm to move downwardly thus rotating all the arms and precipitating the rat into the receptacle 1. It will be noted 15 that each alternate arm or platform is charged with electricity of the opposite character so that a charge will go through the rat when contact is made with the plate 15. The rat is thus killed at the time his 20 front feet are placed on the plate. The momentum of the device causes the arms to revolve until the rod 16 of the next arm, which, in this case would be the arm D, comes into registration with the recess in 25 the top of the collar 5 when the end of the rod will drop into it thus locking the device in position ready to operate on another rat. As soon as the rat receives the shock and his fore feet are withdrawn from the plate 30 15 the circuit is broken. It will thus be seen that the device is charged at all times, but does not use current until actual contact is made. The cost of the current therefore is very slight. When the trap is once baited it 35 is not necessary to make any further adjustments except to remove the bodies of the rats which have been killed by the trap.

I claim:

1. In an electric trap, a central fixed 40 shaft, a sleeve rotatably mounted on said shaft, a series of radially extending platforms carried by said sleeve, means carried by each platform for preventing the rotation of the sleeve, and means for charging alternate platforms with electricity of the same sign and adjacent platforms with electricity of opposite sign.

2. In an electric trap, a central fixed shaft, a locking collar secured to said shaft and being provided with a recess, a sleeve loosely 50 mounted on said shaft and constituting a hub, a plurality of radiating platforms carried by said hub, and locking means carried by each of said platforms and adapted to enter the recess in the collar for preventing the rotation of the hub.

3. In an electric trap, a central fixed shaft, a locking collar secured to said shaft and being provided with a recess, a sleeve loosely 60 mounted on said shaft and constituting a hub, a plurality of radiating platforms carried by said hub, locking means carried by each of said platforms and adapted to enter the recess in the collar for preventing the

rotation of the hub, each of said locking 65 means comprising a pivoted plate, and a gravity operated locking rod pivotally connected to said plate, the lower end of each of said rods being arranged to enter successively the recess in said collar.

4. In an electric trap, a stationary shaft, a hub or sleeve loosely mounted on said shaft, radially extending platforms carried by said hub and being insulated therefrom, a locking collar secured to said shaft, locking 70 means carried by each of said platforms for engaging said locking collar in succession, each of said locking means comprising a pivot plate, and a gravity operated locking rod pivotally connected with said plate 75 and arranged to engage the collar.

5. In an electric trap, a stationary shaft, a hub or sleeve loosely mounted on said shaft, radially extending platforms carried by said hub and being insulated therefrom, a locking collar secured to said shaft, locking 80 means carried by each of said platforms for engaging said locking collar in succession, each of said locking means comprising a pivot plate, a gravity operated locking rod 85 pivotally connected with said plate and arranged to engage the collar, each of said plates having electrical connection with the platform upon which it is mounted, and means for charging adjacent radially extending platforms with electricity of opposite polarity.

6. In an electric trap, a stationary shaft, a hub or sleeve loosely mounted on said shaft, radially extending platforms carried 100 by said hub and being insulated therefrom, a locking collar secured to said shaft, locking means carried by each of said platforms for engaging said locking collar in succession, each of said locking means comprising a pivot plate, a gravity operated locking rod 105 pivotally connected with said plate and arranged to engage the collar, each of said plates having electrical connection with the platform upon which it is mounted, means for charging adjacent radially extending platforms with electricity of opposite polarity, and means carried by each platform 110 for supporting bait, said last named means being disposed between the end of the platform and the pivoted plate.

7. In an electric trap, a stationary shaft, a hub or sleeve loosely mounted on said shaft, radially extending platforms carried by said hub and being insulated therefrom, a locking collar secured to said shaft, locking 115 means carried by each of said platforms for engaging said locking collar in succession, each of said locking means comprising a pivot plate, a gravity operated locking rod 120 pivotally connected with said plate and arranged to engage the collar, each of said plates having electrical connection with the

platform upon which it is mounted, means for charging adjacent radially extending platforms with electricity of opposite polarity, means carried by each platform for supporting bait, said last named means being disposed between the end of the platform and the pivoted plate, and a stationary plat-

form arranged to register with each of said platforms successively when the hub is in its locked position.
